SCREW-OPERATED VISE HAVING A RACK-
ENGAGING NUT-ACTUATED ROCKING
PAWL FOR QUICK ADJUSTMENT

Berthold R. Zitner, Burlington, Iowa

Application April 18, 1946, Serial No. 663,140

7 Claims. (Cl. 81—30)

1

This invention relates to improvements in quickly adjustable vices.

The conventional vise is adjusted by means of a screw which is turned to position the movable jaw of the vise, engaged thereby, relative to the stationary jaw of the vise, to effect the clamping or releasing of the work in the vise. Continuous movement of the adjustable jaw through the turning of the operating screw is both slow and tedious.

It is, therefore, a primary object of the present invention to provide an improved vise mechanism wherein the movable jaw of the vise may be quickly slid into and out of rough positions of adjustment, together with a screw operated mechanism for effecting final clamping adjustments of the vise or release of the vise jaws relative to the work, said mechanism rendering operation of the vise extremely easy and expeditious.

A further object of the invention is to provide a quickly adjustable vise which includes a sturdy pawl member engageable and disengageable with a ratchet plate and so associated with its operating mechanism that a relatively limited movement is required to rock the pawl relative to its ratchet plate.

A further object of the invention is to provide a vise of the character described having simple and effective and easily operated mechanism, which is strong and durable, which is inexpensive to manufacture, and which is well adapted for the purposes described.

With the above and other objects in view, the invention consists of the improved vise, and its parts and combinations as set forth in the claims, and all equivalents thereof.

In the accompanying drawings in which the same reference characters indicate the same parts in all of the views.

Fig. 1 is a view of the improved vise indicated on line 1—1 of Fig. 2 showing the mechanism arranged for the screw feed control of the movable jaw of the vise;

Fig. 2 is a view partly in transverse vertical section taken on line 2—2 of Fig. 1;

Fig. 3 is a view taken on line 3—3 of Fig. 1;

Fig. 4 is a transverse vertical sectional view taken on line 4—4 of Fig. 1 and on a larger scale; and

Fig. 5 is a fragmentary detail sectional view showing the vise pawl disengaged from its ratchet plate whereby quick manual movement of the movable jaw of the vise is permitted.

Referring now more particularly to the drawings, it will appear that the stationary unit of the

2

vise is indicated generally by the numeral 10, and the movable jaw section is indicated generally by the numeral 11. The former includes a box section 12 having a rectangularly shaped opening therethrough. Below the box section there is a flat flanged base portion 13 formed with apertures 14 to permit the securement of the vise to a bench, table, or other support. The forward upper end of the unit 10 is curved and shaped to form a jaw 15. Suitably anchored on a top horizontal surface of the base portion 13 is an elongated ratchet tooth plate 16 whose teeth project upwardly relative to the opening 17 within the box section 12. Said ratchet teeth are angled rearwardly. The plane of the top surface of the teeth 16 is slightly below the bottom of the opening 17 whereby, under certain conditions, a member extended into said opening, and to be described hereinafter, is free to slide longitudinally.

20 The movable section 11 of the vise includes an elongated, rearwardly projecting, rectangularly shaped sleeve 18, a major portion of which is hollow, and which extends into and through the openings 17 of the box section 12, closely fitting 25 the same. A major portion of the bottom of the sleeve 18, over the ratchet plate 16, is open. The forward end of the section 11 has a bore 19 therethrough communicating with the hollow interior of the sleeve. Above said end portion of the unit 30 11 there is an integral curved jaw forming portion 20 directed and arranged so as to be complementary to the jaw 15.

An elongated revolvable rod is indicated generally by the numeral 21. Said rod extends longitudinally through the hollow sleeve 18 and at its forward end, exteriorly of the movable section 11, it is enlarged, as at 21', forming a shoulder in abutment with the outer front face of the section 11. Within the sleeve 18 and adjacent the 40 inner end of the bore 19 there is affixed to the rod 21 a collar 22 which, in cooperation with the rod enlargement 21', serves to hold the rod against longitudinal displacement. A transverse bore 23 through the rod enlargement 21', receives an operating handle 24. The extreme outer end of the rod 21 is journaled within an aperture 25 therefor in the closed rear end of the sleeve 18. An intermediate portion of the rod 21 is formed with screw threads, as at 26, for a purpose herein- 50 after to appear.

A pawl, operatively disposed within the hollow sleeve 18, is indicated generally by the numeral 27. Said pawl is relatively large and massive and is saddle shaped, as best shown in Fig. 4, to 55 permit the free longitudinal extension through

its upper portion of the screw threaded portion 26 of the rod 21. Said pawl is furthermore formed with an upper U-shaped recess 28. The pawl 27 is pivotally and longitudinally shiftably movably mounted on a transverse pin 29 extended through an elongated slot 30 transversely through the base portion of the pawl 27 and having its ends anchored in the side walls of the sleeve 18. The arrangement of the slot 30 and the pin 29 is such as to permit considerable back and forth play or movement during operation of the pawl 27. The lower forward end of the solid base portion of the pawl is formed as a transverse pawl tooth 31 cooperative with selected teeth in the ratchet plate 16.

Within the cavity of the sleeve 18, adjacent the top of the sleeve, are longitudinally extending transversely spaced apart machined surfaces 32 to slidably engage opposite upper side portions of a travelling nut 33. This nut has an internally threaded bore through which the screw threaded portion 26 of the rod 21 extends. The travelling nut 33 is also of a size to be accommodated within the U-shaped recess 28 in the upper portion of the pawl 27. It will be observed from Figs. 1 and 5 that the greatest longitudinal dimension of the travelling nut 33 is somewhat less than the length of the pawl recess 28 and the play thereby permitted is ordinarily taken up by a dished spring disc 34 yieldingly interposed between the rear end of the nut 33 and the inner surfaces of the legs of the pawl 27 thereadjacent. Normally, the expansive force of the spring 34 is such as to maintain the forward end of the nut 33 in engagement with portions of the pawl thereadjacent. It is also to be observed that the front of the travelling nut 33 is curved on a slight radius, as indicated at 33', whereby the pawl may pivot or tilt relative to the nut 33 without binding.

In the operation of the improved quickly adjustable vise, when the parts are in the position shown in Fig. 5, or any other position wherein the pawl is tilted upwardly to free its tooth 31 from the ratchet plate 16, the movable vise section 11 is free for quick sliding movement relative to the stationary unit 10 of the vise. Consequently, by manually grasping the section 11 and by pushing it toward the first vise section 10 a desired distance and into proximity to the work to be clamped between the jaws 15 and 20, a rough adjustment may be quickly accomplished solely by the sliding movement of the sleeve 18 within the opening 17 of the box section 12 of the stationary unit of the vise. Upon quickly attaining the sliding rough adjustment of the movable section of the vise, the work may be clamped between the vise jaws 15 and 20 through a few quick turns imparted to the rod 21 through the operating handle 24. The initial turn of the rod 21 will, because of engagement of the rod with the travelling nut 33, cause said nut to move forwardly relative to the U-shaped opening 28 in the pawl 27 to contact the pawl and cause it to pivot or tilt downwardly to a ratchet tooth engaging position, as in Fig. 1. Through engagement of the pawl with the ratchet plate 16 as described, further turning of the rod 21 in the same direction will cause, because of the anchorage of the rod 21 in the sleeve 18, a movement of the sleeve in a direction to cause the movable section to be drawn toward the stationary unit 10 to thereby tightly clamp the work between the vise jaws 15 and 20. During such clamping movements wherein the screw threaded portion 26 of the rod 21 is transversing the anchored nut

33, the necessary relative movement between the longitudinally moving sleeve 18 and the anchored pawl 27 is permitted by the pawl slot 30. Upon the attainment of the clamping of the work, the rear end of the pawl slot 30 may be in engagement with the pawl mounting pin 29.

When it is desired to release or unclamp the work, it is merely necessary to turn the rod 21 one turn in the opposite direction through manipulation of the handle 24. Such movement of the rod 21 will result in a condition depicted in Fig. 5 wherein the travelling nut 33 exerts a pressure against the spring 34 and against the adjacent portion of the pawl to tilt the forward end of the pawl upwardly and to free its tooth 31 from the ratchet bar 16. Thereupon, through manual engagement of the movable section 11 of the vise and quickly sliding the sleeve 18 within the box section 12, the movable section of the vise may be slid rapidly to any location or distance relative to the stationary vise unit 10, within the range of the vise and to suit the convenience of the operator and work requirements.

The improved quickly adjustable vise is simple and expeditious in operation and the changeover from manual sliding movement of the movable section of the vise to screw control thereof is accomplished by a single quick turn imparted to the control rod 21 in the proper direction. The vise is furthermore strong, durable and effective, minimizes the time required in making vise adjustments and in clamping and releasing work relative thereto, embodies simple, easily assembled mechanism, and is well adapted for the purposes described.

What is claimed as the invention is:

1. A vise, comprising a stationary jaw unit formed with an open box-like section having a toothed portion, a movable jaw unit formed with a sleeve slidably engaging said box-like section, a screw turnably anchored within the sleeve, a travelling nut within the sleeve and arranged for relative sliding movement, the travelling nut being in threaded engagement with the screw, a pawl pivotally associated with the sleeve and engageable and disengageable with the toothed portion of the box-like section, said pawl having a recess therein into which said nut extends for limited longitudinal movement to rock the pawl, and yielding means surrounding a portion of the screw and interposed between adjacent portions of the nut and pawl.

2. A vise, comprising a stationary jaw unit formed with an open box-like section having a toothed portion, a movable jaw unit formed with a sleeve slidably engaging said box-like section, a screw turnably associated with the movable jaw unit and extending through said sleeve, a pawl formed with a recess, means operatively mounting the pawl within said sleeve for engagement and disengagement with said toothed portion including a longitudinal slot in said pawl and a pivot pin fixedly carried by said sleeve and extending through said slot, and a travelling nut in threaded engagement with said screw and slidably engaging said sleeve and extending into said pawl recess, the nut, upon certain turning movements of the screw, being shiftable slightly within said pawl recess to engage the pawl on either side of its axis of pivotal mounting to rock the pawl in either direction for engagement and disengagement with the toothed portion of the box-like section.

3. A vise, comprising a stationary jaw unit formed with an open box-like section having a

toothed portion, a movable jaw unit formed with a sleeve slidably engaging said box-like section, a screw turnably associated with the movable jaw unit and extending through said sleeve, a pawl formed with a recess, means operatively mounting the pawl within said sleeve for engagement and disengagement with said toothed portion including a longitudinal slot in said pawl and a pivot pin fixedly carried by said sleeve and extending through said slot, a travelling nut in threaded engagement with said screw and slidably engaging said sleeve and extending into said pawl recess, the nut, upon certain turning movements of the screw, being shiftable slightly within said pawl recess to engage the pawl on either side of its axis of pivotal mounting to rock the pawl in either direction for engagement and disengagement with the toothed portion of the box-like section, and yielding means interposed between the rear end of the nut and the adjacent portion of the pawl to urge the nut into contact with a portion of the pawl forwardly of its axis of pivotal mounting to normally effect a downwardly rocked position of the forward end of the pawl.

4. A vise, comprising a stationary jaw unit formed with an open box-like section having a toothed portion, a movable jaw unit formed with a sleeve slidably engaging said box-like section, a screw turnably associated with the movable jaw unit and extending through said sleeve, a pawl formed with a socket, means operatively mounting the pawl within said sleeve for rocking engagement and disengagement with said toothed portion including a longitudinal slot in said pawl and a transverse pivot pin fixedly carried by said sleeve and extending through said slot, and a travelling nut in threaded engagement with said screw and slidably engaging said sleeve and extending into said pawl socket, said socket being of slightly greater length than said nut to permit limited lost motion of the nut relative to the pawl.

5. A vise, comprising a stationary jaw unit formed with an open box-like section having a toothed portion, a movable jaw unit formed with a sleeve slidably engaging said box-like section, a screw turnably associated with the movable jaw unit and extending through said sleeve, a pawl formed with a socket, means operatively mounting the pawl within said sleeve for rocking engagement and disengagement with said toothed portion including a longitudinal slot in said pawl and a transverse pivot pin fixedly carried by said sleeve and extending through said slot, a travelling nut in threaded engagement with said screw and slidably engaging said sleeve and extending into said pawl socket, said socket being of slightly greater length than said nut to permit limited lost motion of the nut relative to the pawl, and yielding means in said socket between portions of the nut and pawl to take up said lost motion.

6. A vise, comprising a stationary jaw unit formed with an open box-like section having a toothed portion, a movable jaw unit formed with a sleeve slidably engaging said box-like section, a screw turnably associated with the movable jaw unit and extending through said sleeve, a pawl formed with a socket, means operatively mounting the pawl within said sleeve for rocking engagement and disengagement with said toothed portion including a longitudinal slot in said pawl and a transverse pivot pin fixedly carried by said sleeve and extending through said slot, and a travelling nut in threaded engagement with said screw and slidably engaging said sleeve and extending into said pawl socket, said socket being of slightly greater length than said nut to furnish limited lost motion of the nut relative to the pawl, the forward end of the nut being curved on a radius to permit the pawl to rock on its pivot pin without binding against the nut.

7. A vise, comprising a stationary jaw unit formed with an open box-like section having a toothed portion, a movable jaw unit formed with a sleeve slidably engaging said box-like section, a screw turnably associated with the movable jaw unit and extending through said sleeve, a pawl formed with a socket, means operatively mounting the pawl within said sleeve for rocking engagement and disengagement with said toothed portion including a longitudinal slot in said pawl and a transverse pivot pin fixedly carried by said sleeve and extending through said slot, a travelling nut in threaded engagement with said screw and slidably engaging said sleeve and extending into said pawl socket, said socket being of slightly greater length than said nut to furnish limited lost motion of the nut relative to the pawl, one end of the nut being curved on a radius to permit the pawl to rock on its pivot pin without binding against the nut, and yielding means in said socket between portions of the nut and pawl to take up said lost motion, shifting of the nut within the pawl recess occasioned by certain turning movements of the screw being effective to engage the pawl on either side of its axis of pivotal mounting to rock the pawl in either direction for engagement and disengagement with the toothed portion of the box-like section.
